CLAIM

The ornamental design for a combined mobile phone case and card case, as shown and described.

DESCRIPTION

FIG. 1 is a front and top perspective view of a combined mobile phone case and card case, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view thereof, shown in an alternative position.

The broken lines in the figures illustrate portions of the combined mobile phone case and card case that form no part of the claimed design.

1 Claim, 9 Drawing Sheets
